UNITED STATES PATENT OFFICE.

HENRY BARKSCHAT, OF LOS ANGELES, CALIFORNIA.

MOLD.

1,398,412.

Specification of Letters Patent. Patented Nov. 29, 1921.

Application filed June 30, 1919. Serial No. 307,571.

To all whom it may concern:

Be it known that I, HENRY BARKSCHAT, a citizen of the United States, residing at Los Angeles, in the county of Los Angeles, 5 State of California, have invented new and useful Improvements in Molds, of which the following is a specification.

This invention relates to molds and particularly to molds for making, casting, and 10 forming reinforced concrete posts or other elongated objects of a plastic nature; and relates more particularly, in its specific aspects, to molds adapted for use in the centrifugal process of forming concrete posts 15 and the like. It is a general object of the invention to provide a mold construction strong and durable in its nature, as inexpensive as possible in construction; to provide a separable mold which may be quickly and 20 easily assembled and separated; to provide means for securely and strongly holding the mold together and holding the separable parts in place; and to provide a mold of three or more separable parts for the casting 25 of bodies made of plastic materials by the centrifugal process.

These and other objects of the invention will be best understood by reference to the following detailed description of a preferred 30 form of mold embodying the said invention, reference for this purpose being had to the accompanying drawings in which—

Figure 1 is a longitudinal central section 35 of the mold, showing it assembled and showing the concrete reinforcements in place ready to receive a charge of concrete; Fig. 2 is an enlarged cross-section taken on line 2—2 of Fig. 1; Fig. 3 is an enlarged cross-section taken on line 3—3 of Fig. 1; Fig. 4 is an enlarged cross section taken on line 4—4 of Fig. 1; Fig. 5 is a detail section taken on line 5—5 of Fig. 1; Fig. 6 is a fragmentary elevation taken as indicated by line 40 6—6 on Fig. 1; Fig. 7 is a detail view taken as indicated by line 7—7 on Fig. 5; Fig. 8 is an enlarged detail, part section and part elevation, taken as indicated by line 8—8 on Fig. 3; Fig. 9 is an enlarged detail taken as 45 indicated by line 9—9 on Fig. 1; Fig. 10 is an exterior elevation of the mold; and Fig. 11 is an enlarged section on line 11—11 of Fig. 1.

Although I illustrate this mold in a specific form adapted to the formation of a reinforced concrete post or the like, it will be 50 55 60 65 70 75 80 85 90 95 100 105 110

readily understood that the invention is not limited to this particular and specific use, but may be put to any other use, such as for casting pipe, or in general for casting any elongated object, or any object wherein a mold of the character described may be conveniently used.

For the specific purpose of casting concrete columns, the mold is made with a central barrel or body A, a base box B, and a capital box C.

The body of the mold is made up of a plurality of casing staves 10 and a plurality of mold staves 11 and 12 within the casing 70 staves. The mold staves in this particular case comprise flute staves 12 and spacer staves 11; but the specific formation of the mold staves will of course depend upon the configuration desired to give the exterior of 75 the concrete casting. The casing staves may be secured to each other by wood screws as is indicated at 13; and the mold staves may be secured to the interior surface of the casing by means of screws as is indicated at 14. 80 The composite casing and mold which is thus built up is preferably made in three or more separable sections which part on the line 15, 15, as shown in Fig. 3. These parting lines or surfaces each have an offset 85 portion as shown at 15^a; and in one of the separable parts the offsets are made in opposite directions so that one of the separable parts may be removed directly outwardly 90 without interference from the offset portion. 95 For instance, in Fig. 3 of the drawings the uppermost separable part is shown with such offsets so as to be removable from the other two parts by movement directly upwardly, in the direction indicated by the arrow in that figure. The offsetting of these parting surfaces aids in the accurate registration of the separable parts of the mold and insures an accurately alined interior mold surface. It will be noted that the offset surfaces are side surfaces of the mold staves; they being so spaced and arranged 100 that the offset parting surfaces will come at the joints between them, while the main parting surfaces 15 come at joints between the casing staves 10.

For the purpose of reinforcing the separable parts which have been described, and also for the purpose of providing means for holding the separable parts together, I provide a plurality of reinforcing and encircling segments, which are in the nature of

segmental or curved flanged members with outstanding flanges 21 and with side flanges 22; and wood screws 23 are passed through the flanges 22 and screwed into the casing 5 staves 10 to secure the encircling segments 20 throughout their lengths to the casing staves. These encircling segments are placed upon the casing at suitable longitudinal intervals. Each separable part of the 10 mold body is thus made strong and rigid and is reinforced against distortion, disintegration, or breakage; and all of this is done without the necessity of providing an entire metal casing for the separable parts as has 15 heretofore been usually the case. Such entire metal casings have usually been heavy and bulky, whereas my improved mold construction is now of light weight, and is correspondingly easy to handle; and is inexpensive 20 to make and assemble. The encircling segments are preferably made by taking two angle bars and bending them to the proper curvature and then bolting or riveting them on opposite sides of spacer blocks 20'. These 25 encircling segments further provide the means for securely and tightly clamping the separable parts of the mold together in the assembled formation shown in the drawing. At one end of each of these encircling segments 30 there is pivoted at 25 a draw bar 26 which is preferably provided with a plurality of apertures 27 in its end which projects beyond the end of the encircling segment; and this projecting end is adapted 35 to pass between the flanges 21 of the adjacent end of the adjacent encircling segment. In the flanges 21 of this adjacent encircling segment there are apertures 28 which register with apertures 27 so that a drift pin 29 40 may be driven through the registered apertures. These apertures may so register with each other that if the driving of one drift pin into one set of apertures does not draw the parts sufficiently close together, then another drift pin may be driven into another 45 set of apertures to draw the parts more closely together, and the first driven drift pin, when loosened, may be removed.

The metallic segments 20 are made of such 50 lengths that their ends are not brought together by the clamping action; so that all of the clamping compressing stress is transmitted directly to the opposing parting surfaces of the wooden mold to make tightly 55 closed joints between the separable parts.

The capital box C is constructed very 60 much in the same manner as is the body except that it has a metal cylindrical outer casing or shell 40 made in separable parts 65 corresponding with the separable parts of the casing staves and mold staves of the whole mold. These shell parts 40 are secured to the casing staves 10^a of the capital box by means of screws 23; and certain lower end portions of the shell parts 40

which project downwardly below the staves 10^a and 12^a are secured to the casing staves 10 of the mold body by means of wood screws 41. The casing staves 10^a and mold members 12^a are secured together by screws 70 13^a and 14^a in the manner hereinbefore described. The mold members 12^a may be narrow staves, or may be broader and in the form of segments as I illustrate and describe in the construction of the base box B. The 75 separable parts of the capital box are secured together by a means which is best shown in Figs. 2 and 9; comprising bolt lugs 42 on the edges of the shell parts 40, bolts 43 passing through these lugs, and 80 wedges or drift pins 44 passing through the bolts. The top plate 45 is secured to the capital box shell in much the same manner, by bolts 46 which pass through lugs 47 on shell 40 and pass also through the plates 45, 85 and by wedges 48 which pass the bolt above the plate 45.

The base box B also has an exterior shell made up of separable parts 50 which completely cover the casing staves 10^b and mold staves (or members) 12^b of the base box. The members 12^b are here segments rather than narrow staves; and may be secured to staves 10^b by screws 14^c; staves 10^b being secured together by screws 13^b. The casing 90 staves 10^b are made long enough so that their upper ends overlap the lower ends of casing staves 10; so that a joint of some considerable length is made between the staves 10 and the staves 10^b. The upper ends of 100 the casing parts 50 are provided with a ribbed contracted portion 51 which bears directly upon the outer surface of the casing staves 10; being secured thereto by suitable screws as shown at 52. At 52^a screws are 105 used to secure and hold together the lower ends of staves 10 and the upper parts of staves 10^a. The shell 50 is secured to staves 10^a by screws 23^a. A strong connection is thus made between the parts of the base 110 box and the parts of the main body of the mold—a joint which will not break or open when the separable parts of the mold are handled.

The base box of the mold is provided 115 with suitable means for forming a hollow interior. For instance, I provide a core block 60 which is preferably faced with metal, as shown at 60^a, and is provided for the purpose of forming a hollow in the base. 120 A side opening may be formed in the base by the use of a core block 61 which is held in place by a bolt 62 which extends to the outer surface of the base box and has a nut 63; the nut being removed, and the core block 61 125 being left in the surrounding concrete (shown at 64 in Fig. 5) when the mold part is removed. This core block 61 is removed interiorly into the core opening made by the core block 60 after the core block 60 has 130

been removed. The core block 60 is secured to the bottom plate 65 of the mold, which bottom plate 65 is secured to base shell 50 in the same manner in which top plate 45 5 is secured to capital shell 40. The parts of the base shell are also secured together by the same means as before described by which the parts of the capital shell are secured together. In order to form a depression 10 around the outer end of the opening formed by core block 61, I fasten a small print plate 70 to the inner mold face of the base box. The core block 61 seats back on this plate 70. At the four corners of plate 70 I pass bolts 15 71 through from the exterior of the base box to the inner face of plate 70, these bolts being screwed into anchor lugs 72, which anchor lugs project beyond the inner face of plate 70, and are cast into the concrete when 20 it is formed. Previous to the removal of the mold from the concrete, the bolts 71 are unscrewed from anchor lugs 72 and the anchor lugs are thus left in the formed concrete ready to receive the screws or bolts by which 25 a cover plate is fastened in the depression made by plate 70, to cover the opening made by core block 61. Core block 61, plate 70, and the accompanying bolts, are situated on a center radial line of one of the separable 30 parts of the mold (see Fig. 4) so that the mold part may be moved off the plate, bolts, etc.

In Fig. 1 I show the reinforcing elements 80 in position longitudinally of the mold. 35 These elements 80 are joined laterally by suitable wire connections 81; and the upper ends of elements 80 project through top plate 45 and are there secured by nuts 82 screw-threaded upon the upper ends of the 40 rods 80. The lower ends of these rods 80 are secured to anchors or foot brackets 83 whose lower ends extend out horizontally through the wall of the mold, being held in inverted channel shaped boxes 84 which pass 45 through apertures 85 in the lower ends of the base box directly above the base plate 65. Foot brackets 83 rest directly upon the base plate 65 and screws 86 pass through plate 65 and seat 83 and screw into the boxes 50 84 to hold all of the parts in place. When the mold is disassembled and taken off the completed concrete post, these screws 86 are removed and the boxes 84 removed outwardly so that there is sufficient free space 55 around brackets 83 to enable the mold parts to be removed without interference.

Having described a preferred form of my invention, I claim:

1. A mold comprising a plurality of separable sections, each including longitudinally extending wooden members and segmental metal members extending transversely of and secured to the wooden members, the ends of the metal members on adjacent sections being in alinement when
2. A mold comprising a plurality of separable sections each including a series of longitudinally extending members and a plurality of segmental members, of channel form in cross section, extending transversely of and secured to the longitudinal members, the ends of each of the segmental members of each section being in alinement with the ends of corresponding members of adjacent sections when the parts are assembled to form the mold, and means for retaining the sections in assembled relation including draw bars each pivotally mounted within the channel of one of the segmental members and having one end extending into the channel of the aligned member on an adjacent section and detachably connected to the last said section.
3. In a mold, the combination of a plurality of separable wooden parts, each in segmental form, metallic reinforcing and binding segments secured to and encircling the outside of said separable wooden parts, said metallic segments being secured throughout their lengths to the wooden parts and comprising substantially channel shaped members with radially outstanding flanges, a draw bar pivoted to one end of each of the segments between its flanges and projecting a free end beyond the segment and having apertures through that end, the free end adapted to extend between the flanges of an adjacent segment which have apertures adapted to register with the draw bar apertures, and drift pins adapted to be driven through the registered apertures to draw the segments and the separable parts together.
4. In a substantially cylindrical mold having two parts adjoining end to end and one larger than the other, casing members for the larger part extending over the walls of the smaller part, and a metallic shell for the larger part outside its casing, said metallic shell extending over the part of the casing members which overlap the smaller mold part and having a reduced portion beyond the end of the casing members which reduced portion bears on and is secured to the wall of the smaller mold part.
5. In a separable mold of substantially cylindrical form and having two portions of different size adjoining end to end, the mold being formed in separable segments parting on longitudinal planes, the walls of each portion of each segment being of wood; the wall of the larger portion over-

the sections are assembled to form the mold, and means for retaining the sections in assembled relation including draw bars each pivotally connected at one end to one of the metal members and having its other end overlapping and detachably connected to the aligned metal member of the adjacent section.

2. A mold comprising a plurality of separable sections each including a series of longitudinally extending members and a plurality of segmental members, of channel form in cross section, extending transversely of and secured to the longitudinal members, the ends of each of the segmental members of each section being in alinement with the ends of corresponding members of adjacent sections when the parts are assembled to form the mold, and means for retaining the sections in assembled relation including draw bars each pivotally mounted within the channel of one of the segmental members and having one end extending into the channel of the aligned member on an adjacent section and detachably connected to the last said section.

3. In a mold, the combination of a plurality of separable wooden parts, each in segmental form, metallic reinforcing and binding segments secured to and encircling the outside of said separable wooden parts, said metallic segments being secured throughout their lengths to the wooden parts and comprising substantially channel shaped members with radially outstanding flanges, a draw bar pivoted to one end of each of the segments between its flanges and projecting a free end beyond the segment and having apertures through that end, the free end adapted to extend between the flanges of an adjacent segment which have apertures adapted to register with the draw bar apertures, and drift pins adapted to be driven through the registered apertures to draw the segments and the separable parts together.

4. In a substantially cylindrical mold having two parts adjoining end to end and one larger than the other, casing members for the larger part extending over the walls of the smaller part, and a metallic shell for the larger part outside its casing, said metallic shell extending over the part of the casing members which overlap the smaller mold part and having a reduced portion beyond the end of the casing members which reduced portion bears on and is secured to the wall of the smaller mold part.

5. In a separable mold of substantially cylindrical form and having two portions of different size adjoining end to end, the mold being formed in separable segments parting on longitudinal planes, the walls of each portion of each segment being of wood; the wall of the larger portion over-

lapping the end of the wall of the smaller portion, and a metallic casing for the larger portion extending completely over its wall and having an inwardly offset reduced portion resting on and secured to the wall of the smaller portion, substantially as described.

6. In a mold substantially cylindrical and having two portions of different size adjoining end to end, the mold being formed in parts separable on longitudinal planes; wooden walls for the two portions of the mold, metallic reinforcing and binding segments encompassing the walls of the smaller portion and secured to the outer surfaces of those walls, means at the ends of the segments adapted to draw the segments and the separable parts together, the walls of the larger portions overlapping the walls of the smaller portion, metallic shell segments secured to the outside of the larger portion walls, means to draw said shell segments together, and said shell segments having inwardly offset reduced portions at the ends of the larger portion walls, which reduced portions bear on and are secured to the walls of the smaller portion, substantially as described.

7. In a circular mold, the combination of

a plurality of separable parts with irregular 30 inner molding faces, the several parts meeting on radial surfaces in offset planes presenting shoulders to prevent relative movement between the several parts.

8. In a circular mold, the combination of 35 a plurality of separable parts, the several parts meeting on radial surfaces in offset planes presenting shoulders to prevent relative movement between the several parts; reinforcing and binding segments secured 40 to and encircling the outside of said separable parts, and securing means adapted to draw and hold the segments together.

9. In a circular mold, the combination of 45 a plurality of separable mold parts each embodying an outer course of staves and an inner course of mold-surface-forming staves, the two sets of staves being so placed with relation to each other as to form for each mold part a shouldered edge surface complementary to a similar surface of another mold part.

In witness that I claim the foregoing I have hereunto subscribed my name this 19th day of June, 1919.

HENRY BARKSCHAT.

Witness:

VIRGINIA I. BERINGER.
